L. A. LUPIEN

FASTENING DEVICE

Filed May 8, 1924

Louis A. Lupien Inventor
By his Attorney *Mark D. Bent*

UNITED STATES PATENT OFFICE.

LOUIS A. LUPIEN, OF BROOKLYN, NEW YORK, ASSIGNOR TO EDWIN B. STIMPSON COMPANY, OF BROOKLYN, NEW YORK.

FASTENING DEVICE.

Application filed May 8, 1924. Serial No. 711,764.

To all whom it may concern:

Be it known that I, LOUIS A. LUPIEN, a citizen of the United States, residing at Brooklyn, in the county of Kings and State 5 of New York, have invented certain new and useful Improvements in Fastening Devices, of which the following is a specification.

This invention relates to an adjustable clasp or fastener construction.

10 A general object of the invention is to provide a fastener of the general nature referred to in which adjustments can be readily made and which will securely hold the parts in the relative positions in which they are placed in an adjusting operation.

15 The invention includes a keeper member in the form of a strip of sheet material provided with suitable perforations, and a locking member having two off-set flat portions 20 adapted to take positions, one in front of and the other at the rearward face of the keeper, the keeper passing through a slot intermediate the flat portions. That portion of the locking member at the rear of the 25 keeper is provided with a forwardly extending lug for engagement with the perforations in the keeper. In one form of the invention the locking member also is provided with lugs which extend rearwardly to 30 engage with perforations in the keeper.

Other features of the invention will be hereinafter described.

In the drawings, in which a preferred embodiment of the invention has been selected 35 for illustration,

Figure 1 is a view in perspective showing an adjustable fastener embodying the invention.

40 Figure 2 is a view in longitudinal section of the fastener device taken along the line 2-2 of Figure 3.

Figure 3 is a view in front elevation of the device shown in Figure 1.

45 Figure 4 is a view in perspective of a locking member forming part of a modified form of the invention.

Figure 5 is a view in perspective of a portion of the device shown in Figure 4 and viewing the member from the rear.

50 Figure 6 is a view in longitudinal section of the device taken along the line 6-6 of Figure 7.

Figure 7 is a view in front elevation of the device shown in Figure 6.

55 Referring to the drawings for a more de-

tailed description of the invention, in Figure 1 the two terminal members 10 and 11 of a belt or band are provided respectively with a keeper plate 12 and a locking member 13 for fastening cooperation with the keeper 60 member 12.

The keeper 12 preferably takes the form of a thin elongated strip of sheet metal or other suitable material riveted at one end as at 14 to the band 10 and extending along the 65 terminal portion of the band to the extreme end thereof. The keeper in the form shown in Figures 1 to 3 of the drawing is provided with transversely extending slots 15 forming seats spaced apart at suitable intervals to 70 provide desired differences of adjustment.

The locking member 13 is attached to the other member 11 of the band and includes two relatively flat offset portions 16 and 17, the flat portion 16 being attached to the forward face of the band terminal 11 and bent rearwardly across the end of the band section 11 as at 18 to connect the forward flat portion 16 with the rearward flat portion 17 which in use lies against the rear surface of 80 the keeper member 12 and forward of the adjacent terminal portion 10 of the band or strip. The connecting portion 18 between the flat body portions 16 and 17 of the locking member 13 is provided with a slot 19 85 through which the keeper member 12 extends as is clearly shown in Figures 1 and 2 of the drawing, the keeper thus extending along the rear surface of the terminal member 11. 90

In order to interengage the locking member 13 with the keeper 12 the rearward flat body portion 17 of the locking member is provided with an outwardly or forwardly extending lug member 20 which has the general conformation of the transverse slots or seats 15 in the keeper and which is adapted to be placed in one of the slots to thereby lock the parts in relatively immovable relation to each other. The interengaged position of the parts is shown in Figures 1, 2 and 3 of the drawing and it will be seen that when the parts are in their mutually engaged position the locking member 13 lies in a comparatively flat position with relation 105 to the keeper with which it is interlocked, this position of the parts serving to securely maintain the interlocked condition thereof.

In Figures 4 and 5 of the drawing the forward flat portion 16 of the locking mem- 110

ber 13 is provided with a pair of rearwardly extending lug members 21 which cooperate with the lug 20 on the rearward portion 17 to provide a doubly secure locking relation of the parts. In order to make use of the locking lugs 21 on the forward portion 16 of the locking member the keeper 12 is provided with an additional set of openings 22, as is clearly shown in Figure 7 of the drawing, into which the rearwardly extending lugs 21 project in the locked condition of the parts as is shown in Figure 6 of the drawing. It will thus be seen that a doubly effective locking engagement of the locking member 13 and the keeper 12 is effected by the construction shown in Figures 4 to 7 of the drawing.

In either form of the invention described the operation of adjusting the parts to a new position is readily accomplished by tilting or turning the locking member 13 outwardly so as to disengage the rearwardly extending lugs 21 from their engagement with the keeper 12 and also to disengage the forwardly extending lug 20 from its position in one of the slots 15, the keeper turning for this operation about the rearward edge 23 of the rear portion 17 as a fulcrum. The operation of moving the locking lugs into engagement with a different set of openings can then be readily accomplished whereupon the parts are restored to their relatively flat and parallel positions in which the locking engagement of the parts is securely maintained until a further adjustment thereof is deliberately made.

What I claim is:—

1. In an adjustable fastener, a keeper having the formation of an elongated strip with spaced apart seats, a locking member including two substantially parallel mutually offset and oppositely extending flat members arranged to lie one in front and the other at the rear of the keeper, a connection between said flat members extending substantially at right angles thereto and provided with a slot through which the keeper may extend, a forwardly extending lug on the rearmost flat member having locking engagement with a seat in the keeper and a rearwardly extending lug on the other flat member for engaging another seat in the keeper.

2. In an adjustable fastener, a keeper having the formation of an elongated strip with spaced apart seats, a locking member including two substantially parallel mutually offset and oppositely extending flat members arranged to lie one in front and the other at the rear of the keeper, a connection between said flat members extending substantially at right angles thereto and provided with a slot through which the keeper may extend, an angularly extending lug on one of said flat members for locking engagement with a seat in the keeper and oppositely extending angularly projecting lugs struck from the edge portions of the other flat member for engagement with other seats in the keeper.

3. In an adjustable fastener, a keeper having the formation of an elongated strip with spaced apart seats, a locking member including two substantially parallel mutually offset and oppositely extending flat members arranged to lie one in front and the other at the rear of the keeper, substantially parallel with said keeper and with the member at the rear in flat engagement with the back of the keeper, a connection between said flat members extending substantially at right angles thereto and provided with a narrow slot through which the keeper may extend and a forwardly extending lug on the end of the rearmost flat member for locking engagement with the seats in the keeper.

4. In an adjustable fastener, a keeper having the formation of an elongated strip with spaced apart openings therein, a locking member including two substantially parallel mutually offset and oppositely extending flat members arranged to lie one in front and the other at the rear of the keeper, a connection between said flat members extending substantially at right angles thereto and provided with a slot through which the keeper may extend, a forwardly extending lug on the rearmost flat member having locking engagement with an opening in the keeper, and a rearwardly extending lug on the other flat member for engaging an opening in the keeper.

In testimony whereof I affix my signature.

LOUIS A. LUPIEN.
